UNITED STATES PATENT OFFICE.

THEODOR WEYMERSKIRCH, OF LUXEMBURG, LUXEMBURG.

IRON MOLD FOR CASTING ROLLS FOR ROLLING MILLS.

Application filed August 26, 1921. Serial No. 495,523.

To all whom it may concern:

Be it known that I, THEODOR WEYMERSKIRCH, engineer, a citizen of Luxemburg, residing at and whose post-office address is 5 Differdingen, Luxemburg, Huttenkasino, Luxemburg, have invented certain new and useful Improvements in Iron Molds for Casting Rolls for Rolling Mills (for which I have filed applications in Germany on August 11, 1919; May 10, 1920, and December 6, 1920), of which the following is a specification.

The rolls used in rolling iron of different sections, especially those with deep grooves 15 and with sides which are parallel or almost parallel, are at the present time almost exclusively formed of soft cast iron. Rolls of this type are very seldom made of a hard material or with chilled surfaces, since on forming the grooves or passes all the hard 20 skin is removed and the value of the chilling process entirely lost. Rolls of soft cast iron are, however, exposed to an extremely rapid deterioration in the passes with consequent 25 imperfections in the rolled products.

Attempts to cast chilled finishing rolls with deep passes and parallel sides have not been successful, since the rigid molds used do not allow of provision for the shrinkage 30 of the rolls after casting.

Rolls cast in these molds often break up. More especially, the parts within the passes, that is between two collars, are exposed to 35 an extreme risk of breakage, with the result that the rolls are useless and must be again melted down.

Different processes are known for making grooved rolls in which the molds are divided in the axial direction so that they can expand transversely, but are otherwise perfectly rigid. When rolls are cast in these molds, as soon as the shrinkage commences 40 the parts of the mold are drawn apart to allow an unimpeded shrinkage of the rolls. This work is, however, so dangerous and unsafe that for a long time this method has 45 been abandoned. Usually the withdrawal of the parts takes place too late when cracks are already present, but it often happens 50 that the parts are withdrawn too soon so that the glowing particles break apart. This process is not only very inefficient, but it also introduces a great danger for the operators.

55 Another process depends on the employment of an ordinary smooth, round and

rigid mold in which the rings forming the passes are movably inserted. These rings which in comparison with the usual rigid molds have only a small cross section are 60 very quickly raised in temperature and on expansion are so jammed in the mold that they cannot follow the shrinkage of the rolls. If it be considered how sensitive is the iron mass if only solidified on its outer 65 surface, it will be seen that the smallest restriction can give rise to a rupture. If this restriction is considerable it is certain that the roll, after casting, will be withdrawn 70 from the mold in several pieces. The still fluid metal at the core and the outer solidified surface allow no friction between the ring and mold. Also, in this method no allowance is made for shrinkage within a pass. The process has, also, other considerable 75 drawbacks.

In another process radially arranged iron blocks are inserted in a clay mold which can give to the shrinkage within the pass. In consequence of the great weight of these 80 iron blocks and the usually weak clay sides of the mold, it is extremely difficult to construct with these blocks a mold having several passes arranged over one another. It is almost impossible to construct a perfectly 85 grooved mold with these radial blocks. These molds are not readily portable, since the blocks are suspended without any fixed support in the mold. For these reasons the radial blocks have only come into use for 90 the lower pass of a mold and in consequence of the fact that the blocks are embedded in the clay mold there is no chill. A casting is obtained which is shrunk but only slightly hardened. According to the invention all 95 these draw-backs are obviated and a perfect product can be obtained by simple manipulation and construction.

According to the invention, a rigid mold is employed in order to ensure the correct 100 form of the passes. This rigid mold is divided in the axial direction and also in the transverse direction into as many parts as may be necessary to form the required passes. The joints between the parts are 105 utilized to provide for the shrinkage of the roll in all directions, but more particularly within the grooves.

Some examples of constructions according to the invention are represented in the 110 accompanying drawings.

Figs. 1 and 2 show the difference in the

composition of the material in the known and new rolls.

Fig. 3 is a longitudinal section through a mold according to the invention and

5 Fig. 4 is a cross section of Fig. 3.

Fig. 5 is a longitudinal section through another mold in which the rings are held under spring pressure by movable side bolts.

Fig. 6 is a section on the line 6—6 of 10 Fig. 5.

Fig. 7 is a longitudinal section of a mold in which the rings are carried by vertical bolts.

Fig. 8 shows a section on the line 8—8 of 15 Fig. 7.

Fig. 9 shows a still further subdivided mold on the left in elevation and on the right in a central section.

Fig. 10 is a section on the line 10—10 of 20 Fig. 9.

Figs. 11—13 show on a larger scale details of Fig. 9.

Figs. 14 and 15 show respectively in section and side view another construction of 25 the parts of the mold.

Fig. 16 is a section on the line 16—16 of Fig. 14.

Figs. 17—19 show details of Fig. 14 on a larger scale.

30 Figs. 1 and 2 are sections of cast rolls according respectively to the known and new process in which the hatched parts represent the chilled zones of the pass. It is known that, in the old form of mold in which the

35 rolls were cast cylindrically and the grooves were turned out, only the outer parts of the mold were hard, while with the new method of casting the chilled zone is distributed uniformly over the whole surface of the roll.

40 The mold according to Figs. 3 and 4 comprises rings 1 which are loosely displaceable in a casing 2. The rings 1 are connected with the casing 2 by bolts 3 and springs 4 which pass through sufficiently wide openings 5 so that each ring before and during the casting is carried by the casing 2.

45 After the casting and as soon as the shrinkage begins, the bolts 3 beginning with the upper ring are released sufficiently so that all the rings 1 are completely free. Also, the casing 2 is released at the flanges 6 in order to facilitate the expansion and movement of the rings.

50 55 In order to provide for the shrinkage of the rolls in the axial direction, the rings 1 are provided with a clearance 7, depending on the length of the roll, so that they move in accordance with the shrinkage of the

60 roll. In order that this movement shall be in no way restricted, joints 8 between the different rings are provided with a combustible packing as commonly used in foundries, so that the fluid metal as it rises 65 in the mold cannot enter these joints, but

the packing is already consumed when the shrinkage commences. The construction of the mold shows that in spite of its multiple parts the required roll is made in the simplest possible manner and ensures that 70 the shrinkage after casting shall not give rise to any drawbacks.

In the mold shown in Fig. 5, the rings 1 are fastened by means of spring bolts 3 to guiding rods 9 connected to the cylindrical 75 casing.

In order to give the bolts 3 a better hold, each vertical row of springs 4 bears against a depending rod 10 which is secured to the upper box of the mold. The inner washers 80 11 rest on a rod 12 forming a series of inclined surfaces arranged in steps held by a wedge 13 in contact with the upper flange 14 of the mold.

By driving in the wedge 13 the rod 12 is 85 raised. The washers 11 are moved by the pressure of the springs 4 away from the rod 10, that is, the bolts 3 are loosened. Conversely, by depressing the rod 12, the bolts 3 are tightened. The bolts 15 (Fig. 6) connecting the sections of the rings 1 can be tightened or loosened in the same manner.

In the mold shown in Fig. 7, the rings 90 engaging one over another are arranged in a casing 2 and are held at the required distance apart by nuts 16 which are screwed on vertical bolts 17. The latter are secured by wedges 18 at the flange 19 of the upper mold box. When the wedges are released, the bolts 17 fall into recesses 20 of the lower mold box and the rings 1 are entirely free.

The sections of the rings are, as seen in Fig. 8, connected by bolts 15 which are released by a rod 12.

105 In order to provide a greater radial movement for the rings after they are released they may be beveled (Fig. 5) at their points of engagement with the rod 9, so that they are raised when their guides are depressed. For the same purpose the rods 9 are wedge 110 formed in cross section at the joints of the ring sections as shown in Fig. 6.

In the construction shown in Figs. 9—13, the whole rigid mold *a* is composed of a number of pass rings $1^a, 1^b, 1^c, 1^d, 1^e, 1^f, 1^g$, 115 which can be divided horizontally, and intermediate rings $1^h, 1^i, 1^k, 1^l$.

The different parts of the mold are held in their right position by distance pieces 22 which are threaded on screws 23 and engage 120 in recesses 24 of the parts of the mold. The screws 23 which are rectangular below the thread, in order that the distance pieces 22 may be more easily rotated after the casting is effected, are guided in the upper and 125 lower boxes 25, 26. The lower end of the screw 23 is secured in the lower mold box by wedges 27, while the upper end of the screw 23 is provided with a thread 28 and by a nut 29 presses the upper box 25 on the 130

parts of the mold. In this way all the parts of the mold and the distance pieces in the recesses 24 of the parts are as firmly pressed together as if the mold were made of a single piece.

Even under the greatest pressure which can occur in casting, there can be no displacement of the members of the mold. In this way an absolute security, and therefore, the 10 greatest exactness in the casting of the rolls are obtained. It is important that there should be the greatest accuracy in these grooved rolls since in dual or triple rolls, two or three rolls co-operate together and it is 15 necessary that their passes should correspond as accurately as possible. After casting and when the external surface of the roll is solidified, the nuts 29 on the upper box 25 are released and the screw 23 is rotated through 20 90° to the right or left by means of a lever 30, whereby the distance pieces 22 are swung outwards from the recesses 24 of the parts of the mold (as shown on the right by dotted lines in Fig. 10) and the different parts of 25 the mold are released and rest loosely against and surround the solidified parts of the roll until the cooling is complete.

By this subdivision, the mold can easily follow all the movements due to the shrinkage of the roll without the least hindrance. This method is very important in deep and high passes of which the sides are limited by parallel or approximately parallel collars. The danger of breakage is in this case extremely great. By the arrangement according to the invention, in which the mold within the passes can be subdivided as often as necessary, this danger is quite removed. In these molds the most difficult sections can be 40 cast exactly without the smallest danger of rupture.

In the sectional view of Fig. 9 some constructions of subdivided molds are shown. The pass 1^a represents a preliminary pass 45 for girders, U iron, rails or the like. The central part of the pass is closed by a ring 31 loosely inserted in the two members of the mold. The ring forms also the interior of the mold and allows for the shrinkage of 50 the pass. The pass 1^b represents a round iron pass. The mold members rest on one another at the middle of the passes and externally have a wedge shape. When the pass shrinks the mold members fold towards 55 the exterior so that there is a corresponding clearance within the pass. In order to facilitate this folding the members of the mold are preferably divided axially to form four parts. All the rest of the mold can be made 60 in two parts. Obviously, every part of the mold can be divided axially into as many parts as may be required. 1^c represents a pass for angle iron, four-sided iron or the like. The mold division is here somewhat 65 blunt in order to obtain an easier pass or

mold joint without interfering in the least with the mobility within the pass.

1^d represents a pass for flat iron, U iron or the like. The division of the mold is also in this case stepped. Packing 32 is placed 70 between the joints. The pass 1^e is for sleepers or similar sections. In this case the shrinkage of the pass is allowed for by parallel division surfaces which are closed by a packing 32 on the inside of the mold. The 75 passes 1^f, 1^g are for rails. Also, in these cases the shrinkage of the pass is allowed for in the simplest manner.

Other methods of division can be used for passes of other forms. It is necessary that 80 between the dividing surfaces there should be sufficient play in order to allow for the shrinkage of the roll or pass. The rings are provided (Fig. 10) with flanges 33 connected by screw threaded bolts 3 which can, if 85 required, in dependence on the sensitiveness of the roll to be cast, be provided with springs 4. The axial and horizontal joints within the mold can be made tight with a foundry cement, so that during the casting 90 the iron as it rises cannot enter into these joints. Since the fluid iron quickly solidifies on contact with the walls of the passes, this packing need only operate for a short time. The particles can, therefore, sinter 95 and thereby avoid any restriction during the yielding of the mold.

In such molds rolls can be manufactured with the greatest exactness. The mold has during and after the casting of the roll all 100 the advantages of the rigid molds and also those of the movable molds, since all the danger of binding is removed. These iron molds can be advantageously employed for rolls cast in soft iron. The parts of the 105 molds then receive the form shown in Fig. 11 with a covering 34 of clay particles or other similar materials which are arranged in a more or less thick layer according to the degree of chill required. Also, if only 110 one portion of the mold is provided with the coating 34 it can be advantageously used for rolls which are to receive only a partial chill in the passes. Fig. 12 shows a construction of this kind in which the pass is hardened at the base and only the side surfaces are covered with the coating which provided 115 a softer casting. Fig. 13 shows such a pass for the manufacture of hard collars and soft base in the pass. In order that the particles 120 may be retained at the iron parts of the mold and withstand the upward pressure due to the iron, these parts are preferably provided with dovetailed grooves. These constructions are only given by way of example and can be modified in many ways.

Owing to the great accuracy in which the molds according to the invention can be formed it is possible to use first pass rolls 125 and rolls for billets and the like formed from 130

raw cast passes if the pass need not be exact to some tenths of a millimetre, or if a perfectly neat and smooth section is not required. Such rolls which can be used without removal of the hard skin are not easily damaged and have consequently an extremely long life. For the manufacture of ornamental iron, fashioned fillets, ribbed iron (iron for ferro-concrete) or other roller products which have figures, ribs or the like let into or raised on their upper surface, at the present time steel rolls of mean hardness which allow the surfaces to be cut are almost exclusively used.

According to the invention, it is possible to cast these rolls in chilled castings with sufficient exactness and smoothness. Such figured rolls of hard material outlast several steel rolls, while their manufacture is considerably cheaper because one mold may provide several castings of the same kind of roll. Also, the so-called sharpening grooves, which are usual with first pass rolls for the easier handling of the material to be rolled in the different grooves of the rolls, can be cast at the same time if this does not prevent the shrinkage within the particular grooves. In the construction shown in Figs. 14-19 the different parts of the mold are held in their correct positions by pointed screws 35 which are arranged in blocks 36. The screws 35 are held in the blocks 36 by nuts 37. The blocks 36 are inserted in slots of the screws 23 which are connected by a hinge 40 with the mold. The engagement of the screws 35 in the joints is more clearly shown in Figs. 17-19. As soon as the cast is completed, nuts 38 on the upper end of the screw 23 are released and the screws folded down so that the blocks 36 can be removed with the screws 35. For the easier loosening of the nuts 38 a ball bearing 39 is inserted below them as a washer.

All the described constructions are intended only as examples. The division and the means for holding and releasing the parts of the mold can be altered in many ways without changing the principle of the invention.

Having now particularly described and ascertained the nature of my said invention and in what manner the same is to be performed, I declare that what I claim is:

1. A mold comprising a plurality of rings

for making chilled rolls, characterized by the fact that between the rings clearance is provided, the parts forming the engagement of the rings closing the inner part of the mold and the rings being adapted to follow the shrinkage of the casting.

2. A mold according to claim 1, in which the rings are held by bolts movable under spring pressure, means being provided for permitting the movement of the rings when the casting shrinks.

3. A mold according to claim 1, in which a single unlocking device common to all of the rings or ring sections is provided for releasing or loosening the connection of said rings or ring sections.

4. An iron mold in several parts for casting rolls, in which distance pieces or like members are inserted in the joints of the mold for maintaining the correct disposition of the passes and by means of suitable tensioning members serving also during the casting to join all the parts together to form a rigid structure.

5. A mold according to claim 4 in which the parts of the mold are so arranged within the different passes that they can follow in any direction the shrinkage of the roll after casting.

6. A mold formed according to claim 4, in which exchangeable distance rings are loosely inserted in the joints for giving the required shape.

7. A mold according to claim 4, in which the shrinkage within a pass is allowed for by the members of the molds being arranged close together at the passes and are wedge shaped at their outer surfaces.

8. A mold according to claim 4, in which the parts of the movable mold members covered in known manner with clay or similar particles are provided with dovetailed grooves or similar recesses which ensure the retention of the particles during the casting.

9. A mold according to claim 4, in which the distance pieces can be swung outwards with the screws in order to release the parts of the mold.

In testimony whereof I have affixed my signature in presence of two witnesses.

THEODOR WEYMERSKIRCH.

Witnesses:

A. E. LAVAWITZ,
B. A. LEPICTYES.
